UNITED STATES PATENT OFFICE

JOSEPH E. BLOW, OF LA CYGNE, KANSAS

CLEANER FOR CHICKEN HOUSES

Application filed December 31, 1926. Serial No. 158,269.

The object of my invention is to provide a very efficient, cheap, simple, but sturdy dropping board and cleaner for chicken roosts, and with this and other objects in view 5 my invention consists of the parts and combination of parts as will be hereinafter specified.

In the drawings:

Figure 1 is a top plan view of my improved 10 device.

Figure 2 is a transverse vertical section through Figure 1, on the line 2—2, Figure 1.

The reference numerals 1 and 2 designate 15 standards upon which the dropping boards, cleaner and roosts are supported.

An under frame 3 is secured to the posts which support stringers 4 extending lengthwise of the frame upon which the flooring 5 is secured; there being suitable additional 20 supports or post 6 for the underframe. The flooring constitutes the dropping board. The roosts (not shown) are supported on the standards 1 and 2; and in this connection it will be seen that the posts 2 are passed 25 through the dropping board 5 back from the edge of the board to insure the droppings falling upon the board 5.

At the forward or front edge portion of 30 the dropping board 5, I construct a trough 7 having bottom and side walls, the front edge of the board 5 projecting over said trough as shown. I form an opening 8 through the bottom wall of the trough at one end thereof which will be hereinafter referred to. The 35 trough is divided by a partition 9 extending lengthwise thereof but terminating short of each end of the trough.

At each end of the trough I position stub 40 shafts 10 and 11 upon which are keyed respectively sprocket wheels 12 and 13. A drive chain 14 is mounted upon said sprocket wheels and travels from end to end of said trough 7, and on each side of the partition 9. This chain 14 is provided with drag blades 45 or paddles 15. The shaft 11 is provided with a crank handle 16 by means of which the sprocket wheel 13 is rotated, which in turn drives the chain 14 and through it the sprocket wheel 12.

50 The droppings on the board 5 are brushed,

or otherwise moved into the trough 14, after which the sprocket wheel 13 is rotated by the handle 16, and as the chain is set in motion the blades or paddles 15 are dragged along the trough and carry the droppings with them to the opening 8 in the bottom of the trough through which the droppings fall into a suitable receptacle positioned below said opening.

It will be seen that by the use of my improved device that the cleaning of chicken houses is very much facilitated, and that the refuse is delivered outside of the building without handling.

What I claim is:

In a device of the character described, the combination with a dropping board, a trough partially underlying and partially projecting from one edge of said board, said trough projecting at both ends beyond the ends of the board, a port in the bottom of the trough beyond one end of the dropping board, a longitudinally extending partition in said trough terminating short of the ends of said trough but beyond the ends of the dropping board, 70 a conveyor chain mounted in said trough, and adapted to convey droppings in the trough beyond one end of the dropping board to said port through which they are expelled from the trough.

80 In testimony whereof I affix my signature.
JOSEPH E. BLOW.
